(57) **CLAIM**

I claim the ornamental design for the plush animal—dog, as shown and described.

DESCRIPTION

FIG. 1 is a perspective view of my plush animal—dog; FIG. 2 is a top view thereof; FIG. 3 is a front side elevational view thereof; FIG. 4 is a left side elevational view thereof; FIG. 5 is a right side elevational view thereof; FIG. 6 is a bottom view thereof; and, FIG. 7 is a back side elevational view thereof. The evenly spaced broken lines in FIGS. 1-7 represent stitching and are not intended to form part of the claimed design. The short-long-short broken lines in FIGS. 1 and 3 (in the region of the eyes) represent boundary lines not intended to form part of the claimed design.
